UNITED STATES PATENT OFFICE.

JOHN HARGER, OF HONOLULU, TERRITORY OF HAWAII.

RUNNING-STITCH SEWING-MACHINE.

1,253,173.

Specification of Letters Patent.

Patented Jan. 8, 1918.

Application filed July 9, 1917. Serial No. 179,482.

To all whom it may concern:

Be it known that I, JOHN HARGER, a citizen of the United States, residing at Honolulu, Territory of Hawaii, have invented 5 new and useful Improvements in Running-Stitch Sewing-Machines, of which the following is a specification.

This invention relates to a sewing machine and more particularly to that class of 10 machines known as the running stitch type.

The object is to construct a machine especially adapted to sew strips of paper used for decorative purposes, the strip being crimped and sewed with a single thread, and 15 a stationary needle being employed.

After the sewing and crimping operations are completed in this machine the strip is twisted for forming a round or spiral "lai", as the article is termed in the Hawaiian 20 Islands where it is used for the purpose indicated. It is the present practice to sew these strips of paper by hand, and by employing a machine of the type herein described a large proportion of the time required for the sewing and crimping operations may be saved.

A further object is to provide certain means of novel construction for retaining the needle in proper position, and certain 30 adjusting means hereinafter described.

With the foregoing and other objects in view the invention consists in the novel construction, combination and arrangement of elements hereinafter described and claimed.

35 In the accompanying drawings:

Figure 1 is a view of the machine in side elevation,

Fig. 2 is a top plan view,

Fig. 3 is a side elevation of the rolls and 40 mounting means therefor,

Fig. 4 is an elevation of the paper guiding device,

Fig. 5 is an elevation of the needle bracing device,

45 Fig. 6 is a vertical section of the needle holding device,

Fig. 7 is a transverse section thereof, and

Fig. 8 is a detail of construction described below.

50 Fig. 9 is a detail in section of the structure shown in the lower part of Fig. 5 for guiding the needle brace.

The base on which the operative parts of the machine are mounted is designated 10 55 and at or near one end thereof is a device 12 constituting a paper guide and compris-

ing a frame, the side members of which are designated 13 and 14, these members being properly secured by screws or the like shown at 15. Extending between members 13 and 14 are a plurality of guiding devices 16 and 17 spaced apart and serving to mount the paper guides proper, the guides last named being designated 18 and 19 and each carrying a downwardly depending threaded member 20 engaged by a screw 21 provided with right and left hand threads 22 and 23. This screw has its bearings in the uprights 13 and 14 and is secured at one end by a nut 24, the opposite end carrying a crank 25 provided 60 with a socket member 26 engaging the end of the screw and having a shoulder 27 bearing against one side of the upright 13. This paper guide is designed to accommodate paper of various widths, say from $\frac{1}{4}$ " to 3", 70 the strips of paper to be sewed usually being from 10' to 15' long.

The crimping rolls are mounted in the main frame 30 comprising a central horizontal portion 31, uprights 32 and 33 and laterally extending foot members 34 and 35 secured to the base 10 by means of bolts or the like designated 36. The crimping rolls are designated 41, 42, 43 and 44 and are mounted respectively on shafts 51, 52, 53 and 54, all of the rolls except that designated 44 being rigidly mounted with reference to the shafts and roll 44 being loosely mounted on its shaft 54. The shaft last mentioned is adjustable vertically within slots 45 provided in the frame, these slots being extended laterally as shown at 46 for the purpose of retaining the shaft temporarily when the roll is lifted during the operation described below.

95 Shaft 51 and its roll 41 are adjustable vertically to a limited extent, said shaft being mounted for movement in a rectangular slot in the frame members. The adjustable bearings for this shaft are designated 47, one of 100 these bearings being provided on each side and being under the control of a threaded member 48 extending vertically through the frame and retained in position by a nut 48', a spring 49 encircling the member 48 at that 105 portion below the frame.

The rolls 41, 42, 43 and 44 are each grooved as indicated at 50 these grooves providing for the stationary needle 60 which projects between the upper rolls and the 110 lower rolls.

A crank 61 provides means for imparting

motion to one of the shafts and this motion is transmitted by means of a sprocket wheel 62 driving the chain 63 which in turn drives gear wheel 64. The rolls are in mesh in 5 pairs as shown and provide for the crimping operation. The needle holding device comprises a base portion 70 and an upright or uprights 71 and a needle holding device proper designated 72. This member 72 is 10 channeled as indicated at 73 for the accommodation of the thread passing to the needle, and an adjusting screw 74 has its end portion extending into the channel in alinement with the needle. Extending transversely of 15 the channel 73 is an adjusting screw 74' with which a screw 75 co-operates for retaining the needle. Screw 75 is provided with a head 76 having a knurled edge portion for the purpose of permitting of easy adjustment.

20 Between the needle holding device and the crimping rolls I mount a needle brace the base portion of which is designated 80, the upright or uprights extending therefrom being shown at 81 and carrying a stationary transverse member 82 one end of which is provided with an upwardly extending portion having a flat surface 83 which is grooved at 84, this portion co-operating 25 with the corresponding portion or jaw 85 forming a portion of a pivoted lever 86, the opposite end of which is under the influence of a coiled spring 87 normally holding the jaws of the device closed about the 30 needle. This device serves to retain the needle in proper position with its point in position with reference to the grooves of the rolls.

The thread is designated 90 and passes to 40 the eye of the needle at the point 91.

In operation, the paper guide is adjusted to the width of the paper being sewed and the paper strip is fed into the machine between crimping rolls 41 and 42. The roll 44 45 is raised temporarily to permit enough stitches to accumulate on the needle so that the paper may be stretched out beyond this roll. The latter is then restored to its normal or lower position and during the continued operation of the machine the stitched paper accumulates on that portion of the needle between the rolls 43 and 44 and the needle bracing device. The stitched portion 50 is pulled by hand from the wheels until the needle is filled to its capacity at the point indicated. At this time the needle bracing device is opened by pressing upon the free end of lever 86 and is moved out of the path of the paper strip, the stitched paper being 55 thrust toward the outer end of the needle when the brace is restored to its normal position, and the remaining portion of the strip being operated upon is sewed in the manner described. Finally the needle is removed 60 from the brace and needle holder and the 65

stitched paper is pulled on to the thread. The needle brace proper is movable with reference to the base 80 in view of the slot 88 and the guiding device 89 co-operating therewith.

A U-shaped frame designated 5 is located adjacent to the paper guiding device and the strip passes from this device 5 to the paper guide. The paper usually passes to the machine from a roll of paper merely 70 dropped on the floor, and in order to prevent the strip from passing between the rolls in a twisted position, it is caused to travel over this frame 5 having a depressed central portion 6 which performs the function indicated.

75 It is obvious that any suitable source of power may be used, such as a hand crank, a foot treadle, or a small motor.

80 What is claimed is:

1. In a device of the class described, a plurality of rolls, each provided with an annular groove, said grooves being in alinement, a needle extending between the rolls and co-operating with the grooves, and means for 85 adjustably mounting the needle, said means including a socket portion provided with a longitudinal bore and a longitudinal slot communicating therewith, and threaded members entering said bore from opposite 90 directions and engaging the needle.

2. In a device of the class described, a plurality of rolls, each provided with an annular groove, said grooves being in alinement, means for adjustably mounting certain of 100 the rolls, a needle extending between the rolls and co-operating with the grooves, and means for adjustably mounting the needle, said means including a socket portion provided with a longitudinal bore and a longitudinal slot communicating therewith, and threaded members entering said bore from opposite 105 directions and engaging the needle.

3. In a device of the class described, a paper guiding device, a plurality of crimping rolls, means for driving certain of the rolls, means for imparting movement from one of the driven rolls to another of said rolls, an adjustably mounted roll positioned adjacent to the rolls first named, all of said 110 rolls being grooved annularly in alinement, a needle extending between the rolls and co-operating with the grooves thereof, and means for holding the needle and for bracing the latter between the holding means and the rolls, said paper guiding device including a supporting member, devices movable across the latter in opposite directions, and means engaging said devices last named for effecting the aforesaid movement in one operation.

4. In a device of the class described, a plurality of rolls, means formed thereon for crimping a strip of paper or the like, one of said rolls being mounted for vertical move- 115 120 125 130

ment, an adjustable paper guiding device, a stationary needle projecting between said rolls, adjustable means for mounting the needle, and means for bracing the latter between the mounting means and rolls, said paper guiding device including a supporting member, devices movable across the latter in opposite directions, and means engaging said devices last named for effecting the aforesaid movement in one operation.

5 5. In a device of the class described, a plurality of crimping rolls, a frame for supporting said rolls, means formed in the frame for permitting the vertical movement of certain of the rolls, adjusting means for another of said rolls, driving means for one of said rolls, means for driving another of said rolls from the driven roll, a needle projecting between the rolls, a needle holding device, and a laterally movable needle brace mounted between the needle holding device and the rolls, and comprising a plurality of jaws one of which is pivotally mounted and resiliently operated.

10 6. In a device of the class described, a frame, a plurality of rolls mounted in the frame, a needle means formed on the rolls for crimping a strip of paper to be passed over the needle projecting between said rolls, the rolls being formed with grooves for cooperation with the needle, a needle holding device including oppositely located threaded members for adjusting the butt of the needle laterally and a longitudinally movable member for adjusting the needle lengthwise, and

a two part needle brace movable transversely with reference to the needle.

15 7. In a device of the class described, a plurality of crimping rolls, a needle holding device, a needle mounted therein, and a needle brace mounted between the holding device and the rolls, said brace including a plurality of coöperating jaws, one of which is pivotally mounted, a spring for holding said jaws normally in contact, and means permitting the movement of the brace transversely of the needle.

20 8. In a device of the class described, a plurality of crimping rolls, an adjustable needle holding device, a needle mounted therein, and a needle brace located between the holding device and the rolls, said brace including a base portion, a stationary member mounted horizontally thereon and provided with a grooved jaw, a pivoted jaw coöperating with said stationary jaw and provided with a complementary groove, a spring for holding said jaws normally closed, and means permitting the movement of the brace transversely of the needle.

25 9. In a device of the class described, a plurality of crimping rolls, a needle holding device, a needle mounted therein, and a paper guiding device, said device including a plurality of guides and a reversely threaded element for moving said guides simultaneously toward or away from each other.

In testimony whereof I affix my signature.

JOHN HARGER.
